ALFRED J. A. PETERSON, OF WILKINSBURG, PENNSYLVANIA, ASSIGNOR TO WESTINGHOUSE ELECTRIC & MANUFACTURING COMPANY, A CORPORATION OF PENNSYLVANIA

AUTOMATIC RECLOSED CIRCUIT BREAKER

Application filed April 16, 1923. Serial No. 632,274.

My invention relates to automatic systems for reclosing circuit interrupters and particularly to selective reclosing systems.

One object of my invention is to provide 5 a reclosing system that may be employed with a plurality of feeder circuits to effect the automatic and selective control of any one of the feeder circuits upon the occurrence of predetermined abnormal conditions 10 therein.

Another object of my invention is to provide a system, of the above-indicated character, wherein a single reclosing unit may 15 operate to reclose one feeder circuit at a time in order to preclude an abnormally heavy drain upon a control source of energy, and an excessive shock on the power system.

A further object of my invention is to provide a system, of the above-indicated character, in which a single controlling unit may 20 serve to control a plurality of feeder circuits in a predetermined sequence.

Another object of my invention is to provide a control unit, in a system of the above- 25 indicated character, that shall be operative, upon the occurrence of abnormal conditions in one or more of the circuits to be controlled, to operate the control devices associated with each circuit through a predetermined cycle 30 or schedule before moving to control another feeder subsequently disposed in the predetermined sequence.

Another object of my invention is to provide means whereby a crossed connection be- 35 tween two circuit conductors may be detected and the unit-controlling means rendered inoperative to close the interrupter associated with one of the circuit conductors so long as the crossed connection exists.

40 In practicing my invention, I provide for each circuit of the several feeders a control relay for the closing coil and a lock-out relay for precluding the energization of the coil when a predetermined abnormal condition 45 persists for a predetermined interval of time. I also provide for the control of the several feeders a single control unit comprising a selector relay switch, a timing relay and also what is termed a "set-up" or control relay 50 for the selector. This apparatus is similar

to that shown and described in copending application Serial No. 608,300, filed December 21, 1922, by Charles McL. Moss, William R. Farley and Alfred J. A. Peterson, and assigned to the assignee of the present application. 55

When a circuit interrupter is opened by reason of abnormal conditions in the circuit, the selector actuates a drum controller mechanism to subject the closing coil of the interrupter to the controlling influence of the timing and the set-up relays. The interrupter is thereupon reclosed. 60

If the faulty condition persists and the interrupter opens immediately, the timing 65 and the set-up relay co-operate to effect a second reclosure of the interrupter after a predetermined interval, and, if the interrupter opens again, a third reclosure thereof is effected after another interval. If, after 70 the third reclosure, the interrupter again opens, indicating a persisting faulty condition, the lockout relay associated with the interrupter is caused to operate to preclude further energization of the closing coil. 75

If the interrupter should remain closed after any one of the three reclosures, the timing and the set-up relays will be disconnected from the closing mechanism of the interrupter. If, in the meantime, the interrupter of another feeder circuit has been 80 opened by reason of faulty conditions therein, the selector will move the control of the timing and the set-up relays to a switch associated with the second faulty circuit. The 85 same cycle or schedule of operations is effected until the interrupter of that circuit is either reclosed or locked out.

If the conductors of two different feeder circuits should become crossed, one of the 90 circuits would be immediately disconnected and possibly both by the overload relay devices associated therewith. If both circuits should be disconnected, the reclosing unit would immediately operate to close the interrupter associated with one circuit to reconnect the same to the system. Since the second circuit, with which the now reclosed circuit is crossed, is not energized from the main system, a normal condition will be in- 95 100

dicated in the first circuit and the control unit would move on to the second feeder circuit.

Upon reclosing the second circuit, the crossed connection would be re-established and both circuits would again be re-opened. Since the control unit is still in position to control the second feeder circuit, its interrupter will be reclosed. The second circuit would then remain closed since a normal condition would be indicated in that circuit.

The control unit will, however, again be actuated to move on to effect the reclosure of the first circuit and this procedure will be continued until the crossed connection is clear.

In order to obviate such condition of continual operation, I provide means whereby the reclosing of an interrupter is precluded if the feeder circuit is energized from any source or through any interrupter other than its own source of energy or through its associated circuit interrupter.

Figure 1 of the accompanying drawings is a diagrammatic view of an electrical system illustrating the arrangement of the control apparatus for two feeder circuits connected to operate in accordance with my invention, and

Fig. 2 is a schematic diagrammatic view illustrating, in simplified form, the several circuit connections of the system that is illustrated in Fig. 1.

Referring to the accompanying drawings, energy is supplied from a supply circuit 1 to a plurality of feeder circuits 2 and 3 through circuit interrupters 4 and 5, respectively. The interrupter 4 is provided with a closing coil 10 and a trip coil 11. The circuit of the trip coil 11 is controlled by an overload relay 12 which is energized, in accordance with the current traversing the feeder circuit, through a current transformer 13. The interrupter 4 is also provided with an auxiliary interlock switch 15 that is open when the main contacts of the circuit interrupter are open, and two switches 16 and 17 that are closed when the main contacts of the interrupter are open.

The circuit of the closing coil 10 of the interrupter is controlled by an auxiliary relay switch 18, the operating circuit of which is controlled by a relay 19, which I shall hereafter term the "cut-off" relay.

The function of the cut-off relay 19 is to open the circuit of the closing coil 10 by de-energizing the relay switch 18 after each closure of the interrupter 4.

The relay 19 comprises two switches 20 and 21 that are normally closed and two switches 22 and 25 that are normally open when the relay is de-energized. The relay further comprises an operating coil 23, that serves to actuate the switches 20, 21, 22 and 25 from their de-energized positions, and a holding coil 24 that serves to maintain the switches in their energized positions so long as the holding coil is energized, irrespective of whether

the operating coil 23 remains energized or not. The construction of this relay is such that the holding coil 24 does not have sufficient torque to operate the relay, but merely sufficient to maintain the relay in its energized position after it has been actuated thereto by the operating coil 23.

The interrupter 4 of the feeder circuit 2 is also provided with another relay 26, which I shall hereafter term the "lock-out" relay. The function of the lock-out relay 26 is to preclude further automatic control of the interrupter after a fault occurs and persists beyond the time required to actuate the interrupter through a predetermined cycle of operations.

The lock-out relay 26 comprises two switches 27 and 28 that are open in the de-energized position of the relay, an operating coil 29 that serves to actuate the switches to their respective closed positions, and a holding coil 30 that serves to maintain them in closed position, irrespective of the energization of the coil 29. The construction and the operation of the lock-out relay is similar to that explained above in connection with the cut-off relay 19.

The control apparatus associated with the interrupter 4 comprises further a voltage relay 32 that is energized from a potential transformer 33, the primary winding of which is connected to the feeder circuit 2. The relay 32 is adjusted to require a predetermined time interval in its operation. The relay is provided, in addition to its main contact members, with a back interlock 34.

A resistor 35 is connected in parallel with the operating coil of relay switch 18 to provide an additional current-carrying path for the operating coil of another control relay, as will be hereinafter explained.

The feeder circuit 3 and the interrupter 5 associated therewith are provided with control equipment similar to that enumerated above as associated with the circuit 2 and the interrupter 4. The apparatus that is associated with the interrupter 5 will be referred to by numerals similar to those applied to apparatus of feeder circuit 2 except in the 100 series. For example, the closing coil 10 of the interrupter 4 will correspond to the closing coil 110 of the interrupter 5.

Any number of feeder circuits, equipped with control apparatus similar to that hereinabove described, may be controlled, in any predetermined sequence, by the following apparatus, that is arranged to constitute a single control unit. Such apparatus comprises, in general, a motor-driven sequence switch or selector 51, a set-up relay 52 and a timing relay 53.

The selector 51 comprises a unidirectional motor 54 and a drum controller comprising a plurality of segments 55 that are adapted, in different positions of the controller, to severally engage a plurality of

stationary contact members 56, 57 and 58. To control more feeder circuits, only an additional contact member need be employed on the drum for each additional circuit.

5 The set-up relay 52 is similar in construction and in operation to the cut-off and the lock-out relays 19 and 26 previously described, and it comprises two switches 60 and 61 that are normally open, two switches 62 and 63 that are normally closed, an operating coil 64 for actuating the switches and a holding coil 65 for maintaining them in the position to which they are actuated.

10 The timing relay 53 comprises a motor 68 and a movable bridging member 69 that is controlled thereby through gearing of proper ratio to engage and bridge the three sets of contact members 70, 71 and 72, respectively. The timing relay 53 may be adjusted to cause the bridging member 69 to control the three sets of contact members in a predetermined sequence after predetermined intervals, for example, the relay may be adjusted to effect the bridging of 15 the contact members 70 thirty seconds after the relay is energized, the bridging of the contact members 71 one minute later and the bridging of the contact members 72 two minutes later. These time intervals are 20 specified merely by way of example and they may be respectively adjusted to suit the conditions of any particular system, as desired.

25 The timing relay 53 is of the clutch type and the switch element 69 is immediately reset at its initial position when the relay is de-energized. The timing of the relay is not, therefore, cumulative as between two successive circuits that are controlled thereby.

30 Let it be assumed that the interrupters of the respective feeder circuit interrupters have been closed to energize the associated circuits. Upon the occurrence of abnormal 35 conditions in the circuit 2, the interrupter 4 opens. The following operation thereupon occurs.

35 As will be seen by referring to circuit A of Fig. 2, the circuit of the motor 54 of 40 the selector relay 51 will be energized by the closing of the auxiliary interlock switch 17 of the interrupter 4 to complete a circuit from the positive conductor 75 of a source of control energy through the switch 21 of 45 the cut-off relay 19, the motor 54 and the switch 63 of the set-up relay 52, to the negative bus 76 of the control source. The motor 54 will thereupon actuate the drum until the segments 55 engage the contact members 56 and 57.

50 The operating coil 64 of the set-up relay 52 will thereupon be energized. The circuit thereof may be traced, upon reference to circuits D and G, from the negative control bus 76 through the operating coil 64 of the

set-up relay, contact members 56 and 57 and bridging segments 55, conductor 78, interlock switch 34 of relay 32, switch 20 of the cut-off relay 19, and the operating coil of the relay switch 18 and the resistor 35 in parallel, to the positive conductor 75. The resistor 35 serves to provide an additional current-carrying path that will permit sufficient current to energize the operating coil 64 to operate the set-up relay 52. The relay switch 18, however, is not energized to a sufficient degree to cause it to close.

55 Immediately upon the energization, however, of the operating coil 64, the holding coil 65, which is always energized in series with the resistor 66 between the positive and negative conductors 75 and 76, illustrated in circuit C, serves to maintain the set-up relay 52 in its energized position. The switches 60 and 61 are thereupon closed and the switches 62 and 63 opened. The switch 60 short-circuits the operating coil 64, as will be seen by reference to the circuit D of Fig. 2, and thereupon reduces the resistance of the circuit G including the relay switch 18, sufficiently to permit that switch to close. The closing coil 10 of the interrupter is thereupon energized to close the interrupter.

60 As soon as the interrupter 4 closes, interlock switch 15 closes circuit F to connect the operating coil 23 of the cut-off relay 19 between the positive and negative conductors 75 and 76. The cut-off relay 19 is thereupon actuated to close switch 22 and to open switches 20 and 21. Switch 20, in opening, opens the circuit of the coil of relay switch 18, whereupon the closing coil 10 is de-energized. This operation is illustrated in circuit G of Fig. 2. The cut-off relay 19 is then maintained in its energized position by the holding coil 24, circuit H, the circuit of which is completed from the positive conductor 75 to the negative conductor 76 through a resistor 73, control bus conductor 77, holding coil 24 of relay 19, conductor 78, contact members 56 and 57 and segments 55 of the selector, and switch 60 of the set-up relay 52.

65 If the fault which caused the interrupter to open is cleared, the interrupter 4 will remain closed. If the faulty condition persists, however, the interrupter 4 will immediately be opened by the operation of the over-load relay 12 after a time interval depending upon its time setting.

70 Let it be assumed first that the faulty condition is cleared and that the interrupter 4 remains closed. Under such conditions, the relay 32 will be energized to close its switch after the predetermined interval for which it has been set to operate, for example, two seconds. The switch 32, in closing, short-circuits the holding coil 65 of the set-up relay 52 through conductors 79 and 80, relay switch 32, conductors 78, contact members 56 and 57,

segments 55 of the selector, switch 60 and the holding coil 65 of the set-up relay 52 through conductor 81. The set-up relay 52 is thereupon permitted to return to its initial position to open the switch 60 and remove control potential from the segments 55 of the selector 51. The interrupter remains closed and the control apparatus is de-energized.

Let it now be assumed that the faulty condition of the circuit 2 is a persistent one and that the interrupter is immediately reopened after its first reclosure. The relay 32 has not had sufficient time to close its switch since, normally, its time setting is greater than the time setting of the overload relay 12. The set-up relay 52 is therefore still in its energized position. Switch 61 of set-up relay 52 connected the operating motor 68 of the timing relay 53 between the control conductors 75 and 76 immediately upon the actuation of the set-up relay 52, as is illustrated in circuit B. Since the interrupter 4 was reopened within two seconds after its first reclosure, by reason of the persisting faulty condition, and the set-up relay 52 is still in its energized position, the timing relay 53 will continue to operate until the contact members 70 are bridged by the bridging member 69.

The bridging of the contact members 70 completes a short-circuit around the holding coil 24 of the cut-off relay 19 which has remained energized. The cut-off relay 19 is thereupon permitted to return to its initial position. As illustrated by circuits D and H, the short-circuit around the holding coil 24 may be traced from one terminal of the coil through conductor 78, the contact members 56 and 57 and the segments 55 of the selector, the contact members 70 of the timing relay 53, and conductors 82 and 77 to the other terminal of the coil 24.

When the cut-off relay 19 returns to its initial position, the switch 20 is closed and the circuit of the operating coil of the auxiliary relay switch 19 is re-energized, as previously described and illustrated in circuit G, whereupon the closing coil 10 is energized to reclose the interrupter 4 a second time.

If the feeder circuit 2 should now be clear of abnormal conditions, the set-up relay 52 will be de-energized, as previously described, and the control unit will be available for the control of another feeder circuit. If, however, the faulty condition of circuit 2 still persists, the interrupter 4 will again be opened, and, after a predetermined interval determined by the setting between the contact members 70 and 71, the latter set of contact members will be bridged to effect the third reclosure of the interrupter 4.

As previously explained, the control unit will be disconnected if the feeder circuit is now clear of faulty or abnormal conditions. If the abnormal conditions still persist after such third reclosure, the timing relay 53

will continue to operate until the contact members 72 are bridged. The operating coil 29 of the lock-out relay 26 will thereupon be energized, as illustrated in circuits E and K, from the positive control conductor 75 through the set of contact members 72, of the timing relay 53, a common conductor 83, the operating coil 29 of the lock-out relay 26, switch 25 of cut-off relay 19, conductor 78, contact members 56 and 57 and segment 55 of the selector 51 and switch 60 of the set-up relay 52 to the negative conductor 76.

The lock-out relay 26 is thereupon actuated to its energized position whereupon a circuit is completed by the switch 27 through the holding coil 30 that maintains the latter energized to hold the lock-out relay in its energized position.

Simultaneously, switch 28 of the lock-out relay closes and co-operates with the switch 22 of the cut-off relay 19 which is still in its energized position to short-circuit the holding coil 65 of the set-up relay 52. This circuit, as illustrated by circuits C and J in Fig. 2, may be traced from one terminal of the holding coil 65 through conductor 81, conductor 79, switch 28 of lock-out relay 26, switch 22 of cut-off relay 19, conductor 78, contact members 56 and 57 and segments 55 of the selector, switch 60 of the set-up relay 52 to the other terminal of the holding coil 65 of the latter relay. The set-up relay 52 is thereupon permitted to return to its initial position. In such position, the switch 63 is closed to permit the energization of the selector motor 54 when any other circuit interrupter is opened by reason of abnormal conditions in the associated circuit, as illustrated in circuit A.

Similarly, the closure of switch 62 of the set-up relay 52 short-circuits the motor 68 and the clutch of the timing relay 53 whereupon the bridging member 69 is permitted to return to its initial position. The respective elements 51, 52 and 53 that constitute the common control equipment are now available to control the next interrupter which may be opened.

When the abnormal or faulty condition occurs in only the circuit being controlled, the interrupter may be controlled through a pre-determined cycle of operations and then permitted to remain closed or locked out, depending upon the condition of the circuit. When the abnormal condition, however, is caused by the crossed connection of the conductors of two different circuits, it is necessary to preclude the simultaneous connection of both circuits to the main system or source of energy, since simultaneous connection of both circuits to the system will constitute a short-circuit thereon unless it happens that the crossed conductors be connected to the same phase or to the terminals of like polarity of the source of energy.

If conductor A of circuit 2 and conductor

B of circuit 3 should become cross connected in some manner, the circuit including these conductors would be traversed by an excessive current that would energize the associated overload relays.

- 5 Let it be assumed that the circuit 2 has been traversed by a current heavier than that traversing the circuit 3 and that the interrupter 4 has been opened to disconnect the circuit from the main source of energy 1. 10 The control unit would thereupon be set in operation, as previously described, by the co-operation of the interlock switch 17 of the interrupter 4 and the switch 21 of the cut-off relay 19. However, since the relay switch 32 that is energized from the transformer associated with the conductor A of circuit 2 would be energized by the potential impressed upon the conductor A by reason of its connection to the conductor B of circuit 3, that relay would be in its energized position at which its back interlock 34 would be opened.

25 The operating circuit of the relay 18 would therefore be opened between the contact member 57 of the selector control relay 51 and the operating coil of the relay 18 to preclude the energization thereof so long as the crossed connection continued between the conductor A of the circuit 2 and the conductor B of the 30 circuit 3.

Under such conditions, the reconnection of the feeder circuit 2 to the main source of energy 1 would be precluded but the selector motor relay 51 would be maintained energized 35 and it would continue to rotate so long as the crossed connection continued.

By disposing a switch 90 in a signalling circuit 91 to effect its operation each time the selector motor relay 51 makes one complete 40 revolution, an attendant at the station or a supervisor at a distance may be notified by a signalling device 92 at the station, or by a signal over the circuit of a dispatching system, when an abnormal condition exists which is 45 causing the continuous operation of the selector motor relay. A continuously periodic energization of the signalling device or of the signalling circuit will therefore indicate to the attendant or to the system supervisor the existence of such a condition and an inspector 50 may thereupon be detailed to locate and clear the trouble.

By means of such an arrangement of interlocking circuits, the continual alternate 55 closing of the interrupters associated with two cross-connected circuits and the incidental depreciation of the apparatus and surges on the system may be obviated.

It may happen, under some conditions, that 60 the load upon a feeder circuit is slightly in excess of the normal operating load and that the overload relays associated with the circuit will therefore operate, but only after a relatively long interval of time. By interlocking the energizing circuit of the timing 65

relay switch 32 through the back interlock switch of the associated overload relay 12, the premature disconnection of the control unit may be obviated, to permit the interrupter to be controlled through the predetermined cycle of operations before the control unit moves forward to control another circuit.

In the system which I have illustrated, the circuit interrupters comprise single-pole elements which may be individually controlled. 70 For the sake of simplicity, I have shown merely one of the single-pole breakers associated with different conductors of the two feeder circuits that are illustrated. The several single-pole elements may be arranged to be closed in sequence in a manner similar to the arrangement for the several feeder circuits. For this purpose additional contact members 57^a and 57^b are provided on the drum of the selector relay for the single-pole 75 elements of the interrupter associated with the feeder circuit 2. Similarly, contact members 58^a and 58^b are provided for the other single pole elements of the interrupter 5 associated with the feeder circuit 3.

90 My invention therefore comprehends both the prevention of the premature disconnection of the control unit from the circuit which it is controlling, and also the arrangement of means for detecting a condition of crossed connections between separate circuit conductors and the subsequent control of the controlling unit to preclude the simultaneous connection of both crossed circuits to the main source of energy.

100 My invention is not limited to the specific apparatus illustrated nor to the particular arrangement thereof, since it may be variously modified without departing from the spirit and scope thereof, as set forth in the 105 appended claims.

I claim as my invention:

1. In a power distribution system, the combination with a plurality of feeder circuits, means for opening the respective circuits 110 upon the occurrence of abnormal conditions therein and automatic means for subsequently reclosing the faulty feeder circuits, of means associated with each circuit for detecting a crossed connection between that circuit and another circuit when energized, and means controlled thereby to preclude the automatic reclosure of the first-mentioned circuit while said crossed connection obtains.

2. In a power distribution system, the combination with a plurality of feeder circuits, means for opening the respective circuits upon the occurrence of abnormal conditions therein and automatic means for subsequently reclosing the faulty feeder circuits, of a 120 selector for controlling the automatic reclosure of the feeder circuits after an automatic opening thereof, means for effecting the operation of the selector upon the opening of a 125 circuit, means associated with each circuit 130

for rendering the selector ineffective to re-close said circuit after the opening thereof by reason of a crossed connection with another feeder circuit, and means for indicating a 5 continuous ineffective operation of the selector.

3. In a power system, the combination with a plurality of circuit conductors, a common source of energy therefor and connecting 10 means between said source of energy and the respective conductors, of a selector for controlling the connecting means, means operative when the connecting means are opened to effect the operation of the selector to control the reclosing of said connecting means, and means operative upon a crossed connection between two circuit conductors for rendering the selector ineffective to reclose the 15 connecting means associated with one of the conductors.

4. In a power distributing system, the combination with a supply circuit, a plurality of feeder circuits energized therefrom, a circuit-controlling device provided with closing and 20 tripping mechanism for connecting each feeder circuit to the supply circuit and a common source of control energy for the closing mechanisms, of means responsive to a predetermined abnormal condition in a feeder circuit for actuating the tripping mechanism of the associated controlling device, means for effecting the automatic closure of the several controlling devices singly in a predetermined sequence to obviate a heavy drain on the 25 source of control energy and an excessive shock on the power system and means operative upon the occurrence of a crossed connection between two feeder circuits for rendering the closure-controlling means ineffective 30 in one of said controlling devices.

5. In a power distributing system, the combination with a supply circuit, a plurality of feeder circuits energized therefrom, a circuit-controlling device provided with closing and tripping mechanism for connecting each feeder circuit to the supply circuit and a common source of control energy for the closing mechanisms, of means responsive to a predetermined abnormal condition in a 45 feeder circuit for actuating the tripping mechanism of the associated controlling devices, means for controlling the closing mechanism of the associated devices and unit means for controlling said controlling means singly in a predetermined sequence, and means for rendering the unit means ineffective to operate the controlling means associated with the closing mechanism of one of two circuit-controlling devices associated 50 with two feeder circuit conductors which have became cross connected.

6. In a power distributing system, the combination with a supply circuit, a plurality of feeder circuits energized therefrom, a circuit-controlling device provided with clos- 65

ing and tripping mechanism for connecting each feeder circuit to the supply circuit and a common source of control energy for the closing mechanisms, of means responsive to a predetermined abnormal condition in a 70 feeder circuit for actuating the tripping mechanism of the associated controlling device, means for controlling the closing mechanism of the associated devices and unit means for controlling said controlling means singly in a predetermined sequence, means controlled by each of the feeder circuit controlling devices for initiating the operation of said unit means, and means associated with one of two circuit conductors that have 75 become cross connected for rendering the unit means ineffective to effect the operation of the circuit-controlling devices associated with one of the circuit conductors.

7. In a power distributing system, the combination with a supply circuit, a plurality of feeder circuits energized therefrom, a circuit-controlling device provided with closing and tripping mechanism for connecting each feeder circuit to the supply circuit and a common source of control energy for the closing mechanisms, of means responsive to a predetermined abnormal condition in the feeder circuit for actuating the tripping mechanism of the associated controlling device, means for controlling the closing mechanism of an associated device, unit means for controlling said closing mechanism-controlling means through a predetermined cycle of operation, and a selector for selectively subjecting the mechanism-controlling means to the unit controlling means, and means operative in response to a condition indicative of crossed connections between two feeder circuit conductors for rendering the sequence-controlling means ineffective to control the closing mechanism associated with one of the crossed circuit conductors.

8. In a power distributing system, the combination with a supply circuit, a plurality of feeder circuits energized therefrom, a circuit-controlling device provided with closing and tripping mechanism for connecting each feeder circuit to the supply circuit and a common source of control energy for the closing mechanisms, of means responsive to a predetermined abnormal condition in a feeder circuit for actuating the tripping mechanism of the associated controlling device, means for controlling the closing mechanism of an associated device, unit means for controlling said closing mechanism-controlling means through a predetermined cycle of operation, a selector for selectively subjecting the mechanism-controlling means to the unit controlling means, and means for rendering said selector ineffective to subject one of the mechanism-controlling means to the unit controlling means, comprising means operative in response to a condition of 110 115 120 125 130

crossed connections between the circuit conductor associated with said mechanism-controlling means and another circuit conductor.

5 In testimony whereof, I have hereunto subscribed my name this 29th day of March, 1923.

ALFRED J. A. PETERSON.
